UNITED STATES PATENT OFFICE.

FRANK A. PERSOHN, OF BALTIMORE, MARYLAND.

LENS-MOUNT.

1,339,974.

Specification of Letters Patent. Patented May 11, 1920.

Application filed December 8, 1917. Serial No. 206,135.

To all whom it may concern:

Be it known that I, FRANK A. PERSOHN, a citizen of the United States, residing at Baltimore, in the State of Maryland, have 5 invented certain new and useful Improvements in Lens-Mounts, of which the following is a specification.

This invention relates to improvements in lens mounts for eye-glasses or spectacles 10 and has for one of its objects to provide an improved means for maintaining a lateral strain on the securing screws by which the lenses are held, whereby to very materially lessen the liability of the screws working 15 loose and allow the lenses to rock on the screws.

Another object of the invention is to provide exceedingly simple and cheap means 20 for engaging the rim edge of the lens to exert a constant lateral pressure on the lens in a direction at right angles to the axis of the retaining screws and maintain the lens in proper relation to the bridge.

With these, and other objects in view, the 25 invention is illustrated in the accompanying drawing in which—

Figure 1, shows the inner portions of two lenses with the bridge connecting the same and with my improved device attached 30 thereto,—the parts being shown in front elevation.

Fig. 2, illustrates on an enlarged scale, a vertical section through the improved lens strap and clamp.

Fig. 3, shows the improved lens strap and clamp in edge view and looking between the 35 clamping jaws thereof.

Fig. 4, illustrates in perspective, the detached spring plate that fits between the 40 clamping jaws.

Fig. 5, shows in side elevation the strap and clamp and the attached spring plate, and

Fig. 6, illustrates on an enlarged scale and 45 in front elevation a portion of a lens with my improved device attached thereto.

Referring to the drawing, the numeral 7, designates the lenses having the usual rim-edges 8, and connected by a bridge bar 9, 50 of any preferred form.

Each end of the bridge 9, is connected to a strap 10, which latter has a concave side 11, that conforms to the rim-edge 8, of the lens and said strap is provided with two

clamping jaws 12, which project from opposite edges of the concave sides of the strap.

By reference to Figs. 2 and 3 of the drawing, it will be seen that a tang 13, projects laterally between the jaws 12, from the concave side of the strap,—the tang in this instance being formed by metal punched laterally from the strap but not entirely separated from said strap. This tang 13, therefore has position at the concave side 65 of the strap and between the two clamping jaws 12, as clearly shown in Fig. 3, of the drawing.

In carrying out my invention I employ a spring plate 14, between the concave side of 70 the strap and the convex rim-edge 8, of the lens and this spring plate has a concave-convex shape and is of a width to fit between the clamping jaws 12. A perforation 15, is provided in the spring plate midway 75 between the free spring-ends 16, thereof, and this spring plate is designed to be inserted between the clamping jaws 12, with its convex side confronting the concave surface of the strap so that when in position, 80 the tang 13, on the strap may pass through the perforation 15, from the convex to the concave side of the spring plate and its extreme end then be riveted at the concave side of the spring plate to securely hold the 85 spring plate to the strap and between the clamping jaws 12.

By referring to Fig. 5, of the drawing it will be seen that the curve of the spring plate 14, is sharper or of a smaller radius 90 than the curve of the strap so that the free ends 16, of said plate will extend or project away from the concave side of the strap.

The lenses are provided with the usual screw receiving perforations which are so 95 positioned that when the edge of the lens is inserted between the clamping jaws 12, its rim-edge 8, which has a curve of a greater radius than that of the spring plate, will be engaged by said spring plate ends 16, and 100 these ends will yield as the lens is forced between the clamping jaws to bring the lens perforation into register with the perforation 17, in said jaws. A screw 18, may then be passed through one jaw, then through the 105 lens perforation and finally screwed into the other jaw as is common in lens mountings, to secure the lens between the jaws.

When the lens perforation and the perforation in the jaws are brought into register, the spring plate 14 will be placed under compression so that a constant pressure will 5 be maintained that tends to push the lens and the strap in opposite directions. This constant pressure is therefore placed on the securing screw 18, which has the effect to bind the screw against the walls of the lens 10 perforation and thereby lock the screw against accidental rotation that results in loosening the clamping jaws and allows the lens to rock on the screw. This loosening and rocking of the lens between the clamping jaws is therefore avoided by the use of 15 the spring plate.

It will be noted that my improved means including the strap, spring plate and the means for securing them together is produced from the two parts that may readily be stamped from metal and that the spring plate is securely fastened to the strap against 20

displacement without the use of a third part or fastening device.

Having described my invention, what I 25 claim is,—

The combination with a lens, of a strap having a concave side and two spaced apart clamping jaws projecting from said concave side and straddling the lens,—said strap 30 having a tang projecting from its concave side at a point between said jaws, and a spring plate seated against the strap between the jaws and provided with a perforation through which the tang projects to hold 35 the spring plate against movement with respect to the jaws.

In testimony whereof I affix my signature in the presence of two witnesses.

FRANK A. PERSOHN.
